UNITED STATES PATENT OFFICE.

WILLIAM F. McCARTHY, OF SPRINGFIELD, MASSACHUSETTS.

PAPER-FINISHING MACHINE.

Application filed February 7, 1921. Serial No. 443,207.

To all whom it may concern:

Be it known that WILLIAM F. McCARTHY, a citizen of the United States, residing at Springfield, in the county of Hampden and 5 State of Massachusetts, has invented certain new and useful Improvements in Paper-Finishing Machines, of which the following is a specification, reference being had to the accompanying drawing.

10 This invention refers to machines used in connection with the manufacture of "fine" quality papers, and more particularly to devices for preventing buckling effects, wrinkles and other unevenness of finish taking place on the finished surfaces of such 15 paper while being put through the finishing processes, and incidentally eliminating "broke."

Some of the objects of this invention include the following features:

To provide a device for controlling the supply of stock or material in process, in such a way as to cause it to be introduced into the finishing calenders in a manner best 25 suited for the finishing process and the finished surfaces of the product.

To provide such a device that will be capable of close adjustment both in regard to positioning in several planes and in regulating the tension of the device.

30 To have same readily installable on any general type of calender and adapted for facility in inspection testing, cleaning and removing or repair.

35 To have the device so arranged that one unit will be sufficient for a single calender.

To have the device suitable for installation on present machinery and mechanism used in connection with the present manu- 40 facture of paper.

45 To have a device that will give a more uniform grade of finished paper and one that will automatically, as it were, remove the general conditions that bring about wrinkles, buckling and other serious surface 50 defects, under ordinary conditions, and many other objects which will become apparent as the invention is more fully set forth.

The paper industry is one of a highly de- 55 veloped nature, and one which has received and is receiving the highest degree of technical and practical research. In spite of all the experience and research noted, certain difficulties have been experienced which have rendered that portion of the art of paper-making known as "finishing" of

higher grade papers, a matter of continual uncertainty, because of the frequent finishing of the paper in an unsuitable commercial condition, requiring a discard of the material coming through and accumulation of broke. The matter of broke is serious because when the paper comes through defectively, radical methods have to be introduced to reduce it, in view of the fact that the machine cannot practically be stopped. The paper is torn roughly and in doing so reintroduced into the calenders, where it may repeat and repeat the condition of the disturbed finish. With paper being manufactured in a large paper mill at a high rate of speed, such a condition in the finishing calenders can quickly accumulate an enormous amount of spoiled paper, and consequent loss to all concerned.

75 This invention serves to prevent this condition, by providing that the paper entering the calenders does so in a manner that will assist the stock and at the same time co-operate with the calenders. There is a space between the carrier of paper stock and the calenders or finishing rolls in the usual machine, and while bridging this space certain sags and uneven tensions arise, that bring about a condition for wrinkling very readily in the calenders and is the main cause of the difficulties heretofore mentioned. This invention provides for the bridging of the space and the proper guiding of the material to the calenders, and provides a means for insuring a proper tightness and uniform mobility in entering the finishing rolls.

80 In the drawings, which show by way of example, an embodiment of this invention:

85 Figure 1 is a perspective view of a device embodying this invention, connected with a carrier and set of calenders for finishing paper.

90 Figure 2 is a side view indicating in general the principles and operation of the device.

95 Similar reference characters refer to similar parts throughout the drawings.

In the construction, the reference character 1, represents an upper finishing roll and 2 the lower roll of the set, these rolls or calenders being spaced apart just sufficient to permit the paper stock to pass through and "finished" on their surfaces by the calenders, as noted by the space 3.

100 A carrier 4 is in general proximity to

the calenders and is provided with rolls 5, 7, and 8. Over these rolls run a felt carrier 9, and on this the paper stock 10, flows towards the calenders.

5 The parts just mentioned are indicated in dotted lines in Figure 1 so as not to obstruct the view and position of the device to be described. The arrows in this view indicate the material being processed.

10 Suitably secured to the framework of the machinery or in any other preferable manner, is a bracket or holder 11. This bracket journals a shaft 12, and set screw 13 sets the shaft in the journal. The shaft extends 15 across under the carrier belt and is supported in a like manner at its other end.

A plurality of fastening screws 14 are arranged across the shaft and serve to insert in the slots 15 provided in a plate or 20 apron 16 and hold the same rigidly to the shaft. The apron extends under the roll 7 and is conformed to come close to it as shown at 17, in a quadrantal curve that embraces the lower roll. At this point the 25 apron is extended out horizontally towards the tangential or proximate meeting point of the calenders 1 and 2 and stops close thereto, allowing sufficient space to not interfere with the full introduction of the 30 paper stock going through the calenders. The apron, curve and plate are preferably of one piece and relatively thin so as to give a general resiliency to the device without taking away from its functional ability. 35 Mounted adjustably on the end portions of the shaft 12 are the arms 18. These arms are made preferably of the outline indicated in the drawings. The fastening screws 19 secure the arms in place and the slots 20 in 40 which they stand enable sidewise movement to be made. The plate ends of the arms are formed inwardly as shown at 21 and support the edge portions of the plate.

The operation of the device is as follows:—The device is positioned as indicated 45 in the drawings and the machines started into their various processes. As the stock comes down the carrier 3 it flows on to the feeding plate and then is guided into the 50 calenders and is finished. The plate is preferably at a slight slant pointing towards the space 3. As the stock flows along it becomes tightened and the paper given a uniform stretch. The plate being across the 55 full width of the calender keeps the whole width uniformly and positively feeding in a smooth and flat manner. The plate is positively straight either by its own strength or by the reenforcing action of the arms. 60 The adjustable screws 14 enable the plate to be pushed forward or backward as the stock may require, and to be tightened when the device is properly set.

65 Adjustment in a radial way of the plate may be made turning the whole shaft 12 in

the journals and setting the rotatably acting set-screws 13 firmly in place. Thus the device meets every general requirement of adjustability either to the paper stock or the machinery connected therewith in the finishing.

While but one form of this invention is shown in the drawings, it is not desired to limit the invention to that particular form or in any other way, otherwise than limited 75 by the prior art, as many constructions can be made of this invention that will embody its principles and come within the scope of the appended claims.

Having thus described the invention, what 80 is claimed is:—

1. A finish feeder in combination with a set of calenders, a flat plate extending the length of one of the calender rolls having its feeding edge brought adjacent to the finishing point of the calenders against the roll, and means for adjustably holding the plate in position, and whereby the rough stock will be received thereby and slid thereon, ironed and fed from the plate to 85 the calenders.

2. A finish feeder in combination with calenders and stock flowing through the same comprising a feeding plate, a resilient apron supporting the same and means for 95 adjusting the apron to bring the plate adjacent to the finishing point of the calenders.

3. A finish feeder in combination with calenders a feeding plate having a curve 100 portion in rear of the plate and an apron secured to the curved portion, and means for rotating and adjusting the plate.

4. A finish feeder comprising a plate adapted to receive a relatively large lay of 105 flowing rough stock, an apron attached thereto having a plurality of adjusting points in the rear thereof, a bar supporting the apron at the adjusting points, fastening means in the bar arranged for insertion in the adjusting points of the apron, and means for rotatably raising and lowering the plate on the bar and for holding the same.

5. A finish feeder comprising a flat plate, 115 an apron attached thereto in the rear thereof and arranged to resiliently support the plate, a bar, means for adjustably mounting in a forward and rearward manner the apron on the bar, means for adjusting the bar rotatably and supporting means for the last mentioned means.

6. A finish plate comprising a plate for feeding rough stock into calenders, and an apron projecting rearwardly and curved to 125 receive a stock carrier placed in very close proximity relatively with the calender and engage the stock as it leaves the carrier and support and slide it directly between the calenders at their finishing line.

7. A finish plate feeder in combination with a set of calenders and stock carrier, a plate adapted to fit closely between the carrier and the finishing point of the calenders and provided with a rear apron formed to conform with the contour of the feed roll of the carrier and fit closely thereto and carry the rough stock to the finishing point of the calenders in a smooth and uniform manner, the rear portion thereof being arranged for securing to the framework of the carrier or calenders.
8. A finish feeder comprising in combination with a calender machine and carrier adjacent thereto, a feeding plate having a stock receiving surface formed between the carrier and the calender machine, whereby the rough stock from the carrier may be continuously flowed or carried between the carrier and the finishing point of the calender machine without appreciably allowing the stock to be stressed by its own weight, and means for holding the plate close to the carrier and the upper roll of the calender machine at its finishing line.
9. A device of the class described comprising a plate having a front and rear portion, the front portion being adapted to point to the contact line of the calender rolls and come adjacent thereto, and the rear portion to embrace a carrier for the calender rolls and to extend as an apron therefrom, and a bar supporting the apron portion, and means connected with the bar for adjustably pressing the front portion against the stock as it flows into the calender rolls.
10. A finish feeder for calender machines comprising in combination, a flat feeding plate having its feeding edge at the finishing line of the calender machine, means for adjusting the feeding edge with relation to the finishing line, a cylindrical sleeve holding the plate, a system of journals for holding the sleeve, adjusting screws in the sleeve for rotating the sleeve and causing the plate to press against the upper calender roll of the machines, said set screws being weighted to cause a rotative action in the journal, and means holding the plate in close proximity against the parts of the calender machine whereby the stock will be supported continuously between the carrier and the finishing point or line of the rolls thereof.
11. A device of the class described in combination with a stock carrier and a finishing machine, a plate having a plurality of portions, one of said portions being arranged to carry and guide the stock against the calender rolls, another portion to embrace the carrier contour and take the stock therefrom, and an intermediate portion adapted to carry and guide the stock from the last mentioned portion to the first, and means for keeping the plate in pressing contact with the stock so as to carry and iron it as it passes from the carrier to the finishing machine, and means for adjustably supporting the last mentioned means.
12. A device of the class described comprising a plate having a lip, along the edge of its front portion, said plate being relatively straight, an apiced portion rising up from the rear thereof, and a curved portion extending rearwards from the apiced portion, and an apron extending from the curved portion said apron having a plurality of slots therein, a bar for supporting the apron and having means therein engaging in the slots thereof, and threaded means connected with the bar for giving a rotative adjustability to the bar and the portions of the plate attached therewith, and whereby a pressure may be adjustably transmitted to the lip, and means for supporting all the mentioned means securely with a finishing machine.
- In testimony whereof I hereunto affix my signature in the presence of two witnesses.
